UNITED STATES PATENT OFFICE.

LEMUEL ZACHEUS GRIGSBY, OF MINDEN, LOUISIANA.

POWER-WHEEL.

SPECIFICATION forming part of Letters Patent No. 358,263, dated February 22, 1887.

Application filed October 8, 1886. Serial No. 215,710. (No model.)

To all whom it may concern:

Be it known that I, LEMUEL ZACHEUS GRIGSBY, a citizen of the United States, residing at Minden, in the parish of Webster and State of Louisiana, have invented certain new and useful Improvements in Power-Wheels or Rotary Steam-Engines; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

15 Figure 1 of the drawings is a representation of a side elevation, partly in section. Fig. 2 is an end elevation. Fig. 3 is a sectional detail of the hub. Fig. 4 is a similar detail of the steam-chest. Fig. 5 is a section through 20 the outer plate of the hub, and Figs. 6 and 7 are detail sectional views of the hub and steam-chest.

25 My invention relates to improvements in rotary engines, the object being to make use of gravity for the purposes of economizing power and to prevent the increased friction met with in driving pistons through curved cylinders, as in the usual forms of rotary engines; and it consists in the construction and novel arrangements of parts, hereinafter described, and pointed out in the claims.

30 Referring by letter to the accompanying drawings, A A' designate two vertical standards, in which the engine has bearings, and between which it rotates.

The main features of the engine are as follows:

35 B is a large wheel acting as fly-wheel and as band wheel or pulley, and having a hub, C, in which the cylinders are made or upon which they are secured.

D is a cylindrical or hemispherical steam-chest equal in diameter to the hub and secured thereto. One of the journals is on the steam-chest and the other is on the opposite side of the hub, and these journals have their bearings a a' in the standards A A', respectively, so that the body of the engine forms its own fly-wheel and the rim thereof the driving-pulley or band-wheel.

40 b is the rim of the wheel B, around which a

belt, X, passes. The rim b is connected to the hub by the four equidistant radial arms b', as shown. Within the hub C, preferably of cast metal, are made the two pairs of straight cylinders E E' and F F', the former at right angles to the latter. The cylinders of each pair are parallel to each other, but open in opposite directions, and are equally distant from the center of the hub.

45 The steam-chest D is bolted and packed steam-tight to the hub, and has in its face-plate adjacent thereto the four equidistant ports d, which are near its edge and long enough to extend across the ends of the adjacent pairs 50 of cylinders, each of which communicates with it by a separate port. To illustrate, the pair of cylinders E E' communicate at one end with the adjacent port d, through the openings or passages e e' made in the hub, and at the other 55 end through the similar passages, e' e'', with the opposite port d. The corresponding passages or ports of the pair of cylinders F F' are at one end f f', and at the other end f' f''.

60 Between the hub and the face-plate of the steam-chest are made the deep radial recesses G, into which the ports d and the passages from the cylinders alike open, and in which slide the plate-valves H. The said valves have each an outstanding valve-stem, h, and 65 a curved spring, h', attached centrally to the hub, to move them outward after they have been moved inward, by means hereinafter described.

65 Each valve H has two openings, h² h³, which, when the valves have been driven inward, register with the corresponding passages into the cylinders and allow steam to flow therein. The outer plate, I, of the hub, or the plate opposite the steam-chest, has four exhaust-ports, I', 70 similar to and at points opposite the steam-ports d in the steam-chest, and i i are recesses made in said plate corresponding to the recesses G.

75 J J are valves sliding in the recesses i and provided with the stems i' and springs i'', in all respects similar to the stems h and springs h'.

80 k k' and k² k³ are passages from the ends of the cylinders E E', respectively, similar to the passages e e' and e' e'', the corresponding passages for the cylinders F F' being l l' and l' l''. These passages open into the recess i i. Each

cylinder has a piston, S, reciprocating within it, and each piston is connected by a rod, s, with a weight, T, which, as the rod reciprocates, moves outward and inward on the ways 5 t, made on the corresponding radial arm, b, of the wheel B, as shown. The journal M is fixed centrally to the outer plate, I, of the hub and turns in the bearing a of the standard A, the said journal being preferably solid. The 10 journal M', secured centrally to the outer plate of the steam-chest, is, however, hollow and forms part of the steam-pipe to said chest. This journal turns in the bearing a of the standard A and has on its end, outside of said bearing, a steam-tight coupling-joint, N, which connects with the steam-pipe O, commencing 15 from the boiler, so that it can rotate with the hub C and the wheel B and not lose steam, the throttle-valve being on the pipe O.

20 P is a depressing-plate, fixed to a part of the main frame connecting the standard, at a point where the stems h of the valves H will come in contact therewith just after each of the said valves has passed its lowest point in the direction of rotation. The ends of the stems are rounded or inclined and the plates are correspondingly inclined, so that the stem and valve will be driven inward and the valve opened when the stem comes in contact with 25 the depressing-plate. P' is a similar depressing-plate for the exhaust-valves, which are situated diametrically opposite the steam-valves, as at a point just beyond their highest point in the direction of rotation.

30 Now, it is evident that when the wheel B rotates the pistons of the cylinders E E' will act at the same time; but one will be drawn in as the other is forced out, so that when the steam-valve of said piston opens, just after the 35 said valve has passed the lowest point of the wheel, the corresponding exhaust-valve also opening, the cylinder E will have its piston and attached weight driven outward, and the piston and attached weight of E' will be drawn 40 inward. It being so arranged that E is the higher cylinder, they will make one side of the wheel B overbalance the other and rotation will be maintained. The pistons of the cylinders F F' are actuated in the same manner, so 45 that one side of the wheel is continually overbalancing the other, and consequently its rotation is continuous. As the whole engine rotates, it forms a fly-wheel, O, for itself, and as there are only straight cylinders the engine has 50 the combined advantages of a reciprocating and a rotary engine.

While the engine could be driven by water or compressed air, the use of steam is far pref-

erable, as the depressing-plates could be adjusted to allow the engine to take advantage of the expansion thereof.

Having described this invention, what I claim, and desire to secure by Letters Patent, is—

1. The combination of the main wheel provided with the radial spokes and hub, the cylinders made upon the hub in pairs at right angles to each other, and with the cylinders in each pair acting in opposite directions, the pistons, the weights attached to the piston-rods, 65 and means, substantially as described, whereby the pistons are so actuated as to throw the weights toward the circumference on one side of the wheel only, substantially as specified.

2. The combination of the main wheel provided with the hub and radial spokes having ways for the weights upon them, the cylinders made upon the hub in pairs at right angles to each other, and with the cylinders on each part acting in opposite directions, the weights attached to the piston-rods, the steam-chest secured to and rotating with the hub, the steam and exhaust valves, each communicating with the adjacent ends of the two cylinders of a pair, and means, substantially as described, 75 for opening said valves at the proper points, substantially as specified.

3. The combination of the main wheel, the cylinders arranged upon the hub in pairs at right angles to each other, the steam-chest secured to and rotating with the hub, the steam and exhaust valves provided with stems and springs, as described, and the depressing-plates 80 so situated as to open said valves at the proper points, substantially as specified.

4. The combination of the standards A A', the journal M on the hub having a bearing in the standard A, the hollow journal M' of the steam-chest having a bearing on the standard A', and coupled to the steam-pipe so that it 90 can turn without losing steam, the main wheel B, the hub C, the cylinders E E' and F F', arranged at right angles to each other on the hub, the steam-chest secured to the hub, the weights on the ends of the piston-rods, the steam and exhaust-valves provided with stems and springs, substantially as described, and the depressing-plates to open said valves at the 95 proper points, substantially as specified.

In testimony whereof I affix my signature in presence of two witnesses.

LEMUEL ZACHEUS GRIGSBY.
